(57) **CLAIM**

We claim the ornamental design for anterior lumbar fusion interbody device, as shown and described.

DESCRIPTION

FIG. 1 is a perspective view of anterior lumbar fusion interbody device;

FIG. 2 is a front plan view thereof;

FIG. 3 is a rear plan view thereof;

FIG. 4 is a left side plan view thereof;

FIG. 5 is a right side plan view thereof;

FIG. 6 is a top plan view thereof; and,

FIG. 7 is a bottom plan view thereof.

The dash-dash broken line showing is included for the purpose of illustrating environment and the dash-dot-dash line showing is included for the purpose of showing the bounds of the claimed design, and both form no part of the claimed design.
